ELECTRIC SWITCH

Adiel Y. Dodge, South Bend, Ind.

Application January 9, 1933, Serial No. 650,784

13 Claims. (Cl. 200—152)

This invention relates to electric switches and more particularly to a mercury tube switch comprising means for opening and closing two separate circuits.

5 One object of the present invention is the provision of an improved envelope and liquid separator and, more particularly, the provision of a generally improved and simplified envelope for making selectively one of two contacts and breaking both contacts, which may be formed more economically and expeditiously.

10 Another object is to reduce the operations and labor involved in the formation of these envelopes and to provide an envelope structure permitting 15 the use of heavier glass than heretofore practicable in the manufacture of single contact tubes.

Further objects and advantages of the present invention will appear from the following detailed 20 description, taken in connection with the accompanying drawings, in which:

Fig. 1 is a plan view partly in section of one form of my double contact switch;

Fig. 2 shows the same tube front elevation when level;

25 Fig. 3 shows a front elevation of the tube when tilted;

Fig. 4 is a sectional view on line IV—IV of Fig. 3, showing contact made on the lower side and broken on the upper side;

30 Fig. 5 is a front elevation of the tube when tilted in the opposite direction to Fig. 3;

Fig. 6 is a sectional view on line VI—VI of Fig. 5 showing the lower contact made and the upper contact broken;

35 Fig. 7 shows a sectional view of an optional construction described later;

Fig. 8 shows a sectional elevation of a tube having a different structural arrangement;

Fig. 9 is a sectional view on line IX—IX of 40 Fig. 8;

Fig. 10 is a sectional view on line X—X of Fig. 9;

Fig. 11 is a modified form of Fig. 10;

Fig. 12 is a side elevation of the upper portion of the tube showing the tube tilted to the right;

45 Fig. 13 is a sectional view on line XIII—XIII of Fig. 12;

Fig. 14 is a side elevation of the upper portion of the tube when tilted to the left;

Fig. 15 shows a sectional view on line XV—XV of Fig. 14;

50 Fig. 16 is a fractional sectional view through the mercury channel in general; and

Fig. 17 is a fractional sectional view through the mercury channel in the region where the mercury separates to open the circuit.

55 In the embodiment of Figs. 1 to 6, 20 indicates the bulb or enclosing envelope which is shown as a general C shaped formation. In general these envelopes consist of bent glass tubing with 60 the ends sealed around a suitable electrode. In

referring to the tube as C shaped, it is intended to bring out the fact that it has a long and generally straight central section, preferably having one terminal 1 at its center, and which is looped around at both ends so that the two ends of the tube are in alignment and in close juxtaposition, preferably with the other two terminals 2 and 3 arranged therein.

65 In the preferred form these tubes are bent in the side view so that when lying level, as shown in Fig. 1, the mercury is separated into three bodies, thus breaking electric contact between terminals 1 and 2 and terminals 1 and 3. However, in another form, this same shaped tube may lie flat in the side view and at the bends be provided with an indentation or hump as shown at 70 4 in Fig. 7. Ordinarily this tube is supported in a manner so that it may be tipped to the left about an axis extending through the center of the tube and between the ends of the tube, i. e. 75 through contact 1 and between contacts 2 and 3 as shown in Fig. 3, or, tipped to the right as shown in Fig. 5, or, held in an intermediate position as shown in Fig. 2. When tipped to the left as shown in Fig. 3 electric contact is made by the 80 mercury between electrodes 1 and 3 and broken between 1 and 2. When moved into the position shown in Fig. 5; i. e., tipped to the right, electric contact is made between terminals 1 and 2 and broken between terminals 1 and 3; whereas, when 85 moved into the position shown in Fig. 2 contacts are broken between terminals 1 and 2 and terminals 1 and 3 as shown in Fig. 1.

90 It is common practice in thermostat devices and humidity control devices to use two separate tubes, one completing electric contact at some upper predetermined limit of temperature or humidity; the other tube completing electric contact at some predetermined low limit of temperature or humidity. I propose to accomplish this with 95 one tube by tilting it one way or the other about a central axis. This tube will also be found useful 100 in connection with devices other than those mentioned.

105 In Figs. 8 to 15 is shown a double contact tube of radically different construction accomplishing this same purpose. This improvement consists of means for constructing a mercury contact tube which embodies a porcelain or similar material 14 (Fig. 8) enveloped in a glass chamber 13. Part 14 has a channel for conducting mercury between electric terminal points in such manner that one electric circuit may be closed shortly after the opening of another on the opposite side. To this extent this construction accomplishes the same 110 results as does the construction shown in Figs. 1 to 7, inc.

115 But, in addition to the above, the construction shown in Figs. 8 to 15 provides means for closing one or two electric circuits when the tube is in 120

- the level or neutral position as well as closing one circuit when tipped to the right and another circuit when tipped to the left. The circular path in which the mercury flows may be of the form shown at 12 in Fig. 16. Electrodes 5 and 8 in Fig. 10 may be located so that they will lie within the mercury bath when tube is level by placing them to the right and to the left of the jump in Fig. 10, or they may be placed as indicated at 9 and 10 (Fig. 11) outside of the mercury bath when the tube is level by placing them more nearly the crest of hump 11 (Fig. 11). The purpose of this hump or rise in the mercury channel is to cause the mercury to break or separate in their proximity when the tube is level and to cause a more rapid break at the time mercury separates as tube is tipped from the contact position in question.
- It is to be understood that the embodiments of the invention herein set forth are presented for the purpose of illustration only, and various changes may be made therein without departing from the spirit and scope of the appended claims.
- I claim:
1. A mercury switch having a tilttable member having formed therein a curved reservoir containing mercury and having its ends in alinement and in close juxtaposition, and at least three contacts extending into said reservoir and adapted to be immersed in the mercury therein and two of which are arranged in said ends, said member being arranged for tilting movement about an axis extending midway between two of the contacts.
2. A mercury switch comprising a C-shaped reservoir containing mercury and having a central section looped around at both ends and having its ends in alinement and close juxtaposition, and having a contact in each end and one in said central section approximately at its center, and mounted to be tilted about an axis extending through the center contact and substantially midway between the end contacts.
3. A mercury switch comprising a C-shaped reservoir containing mercury and having a central section looped around at both ends and having its ends in alinement and in close juxtaposition, and having a contact in each end and one in said central section approximately at its center, and which is constructed and arranged when level to break up the mercury into three disconnected bodies in which the three contacts are immersed respectively.
4. A mercury switch comprising a C-shaped reservoir containing mercury and having a central section looped around at both ends and having its ends in alinement and in close juxtaposition, and having a contact in each end and one in said central section approximately at its center, and which is bent upwardly where it is looped around to connect the ends to said central section so that when level the mercury breaks up into three disconnected bodies in which the three contacts are immersed respectively.
5. A mercury switch comprising a C-shaped reservoir containing mercury and having a central section looped around at both ends and having its ends in alinement and in close juxtaposition, and having a contact at each end and one in said central section approximately at its center, and having indentations between the cen-
- ter contact and the end contacts respectively, such that when the reservoir is level the mercury is broken up into three bodies in which the contacts are immersed respectively.
6. A mercury switch comprising a C-shaped sealed glass tube containing mercury and having a central section looped around at both ends and having its ends in alinement and in close juxtaposition, and having a contact at each end and one in said central section approximately at its center, and having constrictions between the center contact and the end contacts respectively, such that when the reservoir is level the mercury is broken up into three bodies in which the contacts are immersed respectively.
7. A mercury switch comprising a tilttable sealed tube, an element mounted in said tube and having in its upper face a curved horizontal groove containing mercury, and contacts projecting into said groove, in combination with means for oscillating the tube to cause the mercury to flow around said groove to connect the contacts when the tube is in one position and to break the connection between them when the tube is in a different position.
8. A mercury switch comprising a tilttable sealed tube, an element mounted in said tube and having in its upper face a circular groove containing mercury, and two pairs of contacts projecting into said groove and selectively electrically connected by tilting said tube.
9. A mercury switch comprising a tilttable member having a curved groove in its upper face and having humps in the bottom of said groove to break up the mercury into separated bodies when said member is level, and contacts beside said humps.
10. A mercury switch comprising a tilttable member having a curved groove in its upper face and having humps in the bottom of said groove to break up the mercury into separated bodies when said member is level, and contacts adjacent and on opposite sides of said humps and which are immersed in said separated bodies of mercury when the tilttable member is level.
11. A mercury switch comprising a tilttable member having a curved groove in its upper face and having humps in the bottom of said groove to break up the mercury into separated bodies when said member is level, and contacts passing through the ends of said humps out of the mercury when said member is level and immersed in the mercury when said member is tilted to cause the mercury to flow over the hump.
12. A mercury switch comprising a sealed tube containing a non-conducting member formed in its upper face with a ring-shaped groove containing mercury, and having contacts extending into said groove.
13. A mercury switch comprising a tilttable member formed to provide a curved reservoir containing mercury, means at the sides of the reservoir furthest from the axis of tilting for breaking up the mercury into separated bodies adjacent said axis and with said sides clear of mercury when the tilttable member is level, and contacts extending into the reservoir on opposite sides of said means and connected by the mercury when the member is tilted to cause the mercury to flow over said means.

ADIEL Y. DODGE. 145
